UNITED STATES PATENT OFFICE

149,119

DESIGN FOR A WASHING MACHINE OR
SIMILAR ARTICLE

Peter E. Geldhof, St. Joseph, Mich., assignor to
Nineteen Hundred Corporation, St. Joseph,
Mich., a corporation of New York

Application December 7, 1946, Serial No. 135,337

Term of patent 14 years

(Cl. D49—1)

To all whom it may concern:

Be it known that I, Peter E. Geldhof, a citizen of the United States and a resident of the city of St. Joseph, in the county of Berrien and State of Michigan, have invented a new, original, and ornamental Design for a Washing Machine or Similar Article, of which the following is a specification, reference being had to the accompanying drawing, forming a part thereof.

On the drawing:

Figure 1 is a perspective view of the front, right side and top of a washing machine or similar article embodying the novel design of my invention;

Figure 2 is a perspective view thereof showing the left side and top of the machine;

Figure 3 is a perspective view showing the rear and top of the machine; and

Figure 4 is a perspective view showing the top and rear of the machine.

I claim:

The ornamental design for a washing machine or similar article, as shown.

PETER E. GELDHOF.
